UNITED STATES PATENT OFFICE.

FRANK W. CAMERON, OF FRANKFORT, NEW YORK.

HOE-ROLLING MACHINE.

No. 848,630.

Specification of Letters Patent.

Patented April 2, 1907.

Application filed September 23, 1905. Serial No. 279,755.

To all whom it may concern:

Be it known that I, FRANK W. CAMERON, a citizen of the United States, residing at Frankfort, in the county of Herkimer and State of New York, have invented certain new and useful Improvements in Hoe-Rolling Machines, of which the following is a specification, reference being had therein to the accompanying drawings.

My invention relates to an improved hoe-rolling machine; and I declare that the following is a full, clear, concise, and exact description thereof, sufficient to enable one skilled in the art to make and use the same, reference being had to the accompanying drawings, in which like letters and numerals refer to like parts throughout.

My invention relates particularly to the combination and arrangement of lever connections to take the place of pinion-gears, and is particularly applicable to such machines, though it may be also used in other connections or circumstances where like results are sought. I therefore do not limit myself to this particular showing of my device.

The purpose of my invention is to render the operation of the machine more certain, efficient, easy, and prompt, whereby I am able to avoid certain defects in the machines now being used—for instance, in the manufacture of hoes—and to manufacture the product with exactness and uniformity.

The invention will be fully disclosed in the following description, which is to be read in connection with the drawings, in which like letters and numbers refer to like parts throughout.

Figure 1 is a perspective view of a familiar machine having my improved device mounted thereon. Figs. 2 and 3 are side views showing the devices in extreme operative positions, the medium position being shown in Fig. 1. Fig. 4 is a side view in section on the line xx of Fig. 5, which latter figure is a front view of the device in the position shown in Fig. 3.

Referring to the figures more in detail, A A represent the housings of the machine, which are provided with integral or attached bases A'. These housings are of the proper form and size and arrangement to support transversely the two rollers B and B', the latter of which is mounted in suitable journals (not indicated, but readily understood) and the upper of which is mounted in boxes which are adjustable vertically in the hous-

ings by turning gears C on the screws C' and between which is the pinion c on stud c'. The screws are provided with yokes C'', which support rods c'', which extend downward to support the box c''', which carries the upper roller. It will be understood that these parts are duplicated at each end of the upper roller and that each end of the lower roller is provided with duplicate journals and gears. 65 These rollers are also shown in Fig. 5, and they are intended to support the dies D, which are so fashioned that as the rollers turn the dies open and shut in their swing with the roll, so that metal passed between 70 the dies is rolled to the proper thickness and size. The rollers extend beyond the housings, as seen in Fig. 5, and are provided with dies, as indicated, but not particularly described. These particulars are common in 75 machines of this character.

C''' is a lever-arm operatively connected with one of the gears C, by which the train is operated to raise or lower the upper roller to regulate the thickness to be given to the 80 metal between the dies.

E represents the shaft, which has a fly-wheel (not shown) and a gear E', from which the shaft receives its power and which shaft carries crank-arm E'', which has the pitman 85 F, which extends to and is connected with one or more arms F', connected to the lower roller, so that the reciprocating movement imparted to the shaft rocks the lower roller to and fro. Of course any suitable mechanism is appropriate to accomplish this result, it being suitably formed and arranged for the purpose.

Heretofore the outer ends of the rollers have carried pinion-gears which intermeshed 95 and the lower of which, turning with the lower shaft, imparted motion to the upper roller or shaft. The difficulty has been that there was loss of motion in this form of device and an unnecessary use of power 100 and that the dies in their turning to and fro would not be accurate in their interplay and that the gears especially would become rapidly worn and the operation of the machine be more and more variable and more 105 inaccurate. To obviate this and procure greater leverage, I mount on the lower shaft crank-arm 1 and on the upper shaft crank-arm 2. Each housing is provided with an abutment 1^a, which may be integral or attached and which housings carry a shaft 1^b. On this shaft I mount an elbow or bell-crank

lever 3, to the opposite ends of which I connect by links 4 and 5 the crank-arms 2 and 1, which are constructed to give the proper throw to the connected crank-arms, and so that the reciprocation of the bell-crank lever 3 will open or close the dies on the rollers or shafts. In other words, the lower roller being reciprocated by the pitman F will through the connection described reciprocate oppositely the upper roller and die. It may be noted that the center points of the bearings of the crank-arms 1 and 2 are equal and that the like distances on the arms of the bell-crank lever 3 are equal. As stated, Figs. 2 and 3 indicate the different positions of this device, and the construction and operation will be clear to one skilled in the art.

A great advantage of the invention lies in the fact that the reciprocation of each roller is synchronous and exact in extent and that thereby the dies operate with uniformity, and there is no play by which one die can start its movement ahead of the other by reason of any play between the teeth of the pinions, which have been heretofore used on the rollers or shafts.

A considerable item has been the necessity of replacing worn pinions, as every particle of wear would affect the operation of the dies, and it will be seen that the device I employ obviates any such objection. It should be further noted that this device can be readily applied to any of the old styles of machines

and answers all of the requirements, while its operation is far more accurate and economical in the use of power. 35

Variations and modifications will be apparent to those skilled in the art, intending to include in this illustration all applications, modifications, and variations which 40 may be used without departing from the spirit and scope of my invention.

Having described my invention, what I claim as new, and desire to secure by Letters Patent, is—

1. In a device of the character described, having die-bearing rollers, a crank-arm mounted on each roller and a bell-crank with link connections between the same and the said crank-arms to reciprocate the latter to 50 and fro.

2. In a device of the character described having rollers and means to reciprocate one of the same, a bell-crank lever, and operative connections between the arms of the said lever and the rollers whereby to transmit power from the reciprocated roller to the other roller to reciprocate the latter instantaneously with the action of the former roller. 55

In testimony whereof I affix my signature in presence of two witnesses.

FRANK W. CAMERON.
